ATTORNEYS

UNITED STATES PATENT OFFICE.

RICHARD F. CLARK, OF CHICAGO, ILLINOIS.

DESIGN FOR A HUSKING-PIN.

SPECIFICATION forming part of Design No. 32,483, dated April 10, 1900.

Application filed January 18, 1900. Serial No. 1,941. Term of patent 14 years.

To all whom it may concern:

Be it known that I, RICHARD F. CLARK, a citizen of the United States, residing at Chicago, in the county of Cook and State of Illinois, have invented and produced a new and original Design for Husking-Pins, of which the following is a specification, reference being had to the accompanying drawings, forming part thereof, and in which—

Figure 1 is a face view of a husking-pin, showing my new design; and Fig. 2 is a cross-section on about line 2 2 of Fig. 1.

The design consists in the unitary article illustrated in the drawings and characterized

by the body portion B, made concavo-convex 15 in cross-section, as shown in Fig. 2, with the head A at one end tapered down to a point and projecting diagonally from the longitudinal line of the pin.

Having described my invention, what I 20 claim as new, and desire to secure by Letters Patent, is—

The design for a husking-pin, as herein shown and described.

RICHARD F. CLARK.
